HENRY S. VROOMAN, OF BOSTON, MASSACHUSETTS.

Letters Patent No. 89,818, dated May 4, 1869.

IMPROVED SOLE-CHANNELLING AND FEATHER-EDGING MACHINE.

The Schedule referred to in these Letters Patent and making part of the same.

To all whom it may concern:

Be it known that I, HENRY S. VROOMAN, of Boston, in the county of Suffolk, and State of Massachusetts, have invented Improvements in Sole-Channelling or Feather-Edging Machines; and I do hereby declare that the following, taken in connection with the drawings which accompany and form part of this specification, is a description of my invention sufficient to enable those skilled in the art to practise it.

This invention has particular reference to so arranging an ordinary channelling-machine, for channelling the soles of boots and shoes, preparatory to sewing the uppers thereto, that the guide for the edge of the sole may be adjusted, to vary the distance of an ordinary channel from the edge of the sole, or the width of a chamfer at the edge of the sole; also, to providing a rest for the under side of the sole in the intermediate space between the edge-guide and the toothed feed-wheel, and to so constructing this rest that a knife attached to the upper portion or arm of the machine will pass down below the sole, and skive, chamfer, or bevel the under surface at the edge; also, to a provision for adjustment of the upper smooth presser or feed-wheel horizontally, with reference to the edge-guide, and to the arm by which it is supported.

That part of my invention relating to a movable edge-guide for the sole I regard as preferable, either for ordinary channelling on the upper surface of the sole, or skiving the under surface, to the provision I have already patented, January 1, 1867, for moving the arm horizontally, to adjust the cutters in their relation to the edge-guide, in that the same result can be produced without changing the relation of the cutter or cutters to the toothed feed-wheel carrying the sole.

My invention is not, broadly, in such an arrangement of mechanism as shall cause the sole to be bevelled or skived on the under surface thereof, such an arrangement having been made by one J. B. Sias, of Beverly, Massachusetts, previous to my invention. In said Sias' arrangement, however, there was no effective provision for allowing the knife to pass under the edge of the sole, or for cutting the chamfer more or less distant from the edge of the sole.

The drawings represent the parts of a channelling-machine with which my improvements are directly embodied.

A shows a side and sectional elevation of the feed-wheels and adjacent mechanism.

B is a section on the line x x.

C is a plan of the lower feed-wheel, the edge-rest, and the edge-guide.

a denotes the front post of the machine, in which is the bearing, b, for the shaft of the lever or toothed feed-wheel c.

d is the movable arm, carrying the pin or shaft of the upper or smooth-faced feed-wheel e, the arm dropping by its weight, until the surface of the upper roll

is at such distance from the adjacent surface of the lower roll as to cause the upper wheel to be raised by the insertion of a sole between the wheels, the weight of the upper wheel and the arm d, or downward pressure brought to bear upon the arm, causing the sole to be pressed against the teeth of the wheel e, so as to insure its feed-movement to the action of the cutter.

f denotes the rest which supports the edge of the sole to be bevelled or skived.

In the ordinary and well-known McKay channellers, as the cutter works upon the upper surface of the sole, the lower surface of the sole adjacent to the edge is supported upon a smooth rim which is made upon the toothed feed-wheel beyond the teeth, the sole next to its edge being supported upon this surface. It will be obvious, however, that the wheel cannot be so made in this machine, because the beveling-cutter must occupy the space just below the edge of the sole.

I therefore make the lower feed-wheel narrow, and project from the post a a stationary rest-plate, f, which comes up to the wheel with its upper surface flush, or nearly so, with the top of the wheel, as seen at A.

Through a slot, g, in this rest-plate (or down by the side of the plate, if it be made narrow,) extends the beveling or skiving-cutter h, the shank of the cutter being bolted to the arm d.

i denotes the edge-guide, against which the edge of the sole is held as it is fed to the action of the cutter, its position determining the width of the skiving, and the distance of the channel from the edge of the sole, when any kind of channelling-cutter is used.

To vary the width of the skiving, or the distance of the channel from the sole-edge, without moving the rest, this guide is made movable, and adjustable in position upon the rest-plate, by means of a slot and screw, k.

The guide is slotted, as seen at l, to allow the shank of the cutter to drop through it.

To adjust the upper feed-wheel to correspond to the position of the edge-guide, that is to say, to keep the wheel up to the guide, and without moving the arm, I mount the wheel on a screw-pin, m, on which it turns loosely, the wheel, in its rotation, being confined between the head, n, of the screw and a collar, o, and screwing into the arm d, as shown at A.

By turning the screw shown, the wheel is moved toward or from the guide, and, as the guide is moved back, the wheel may be moved up to it, so as to bear upon the whole upper surface opposite to which the cutter h is acting.

It will be obvious that a plain pin, carrying the smooth feed-roll, and adjustable horizontally within the arm, and fastened in any one position by a set-screw, may be used instead of the screw m.

By these means, it will readily be seen that, while the cutter is arranged so as to skive the lower surface of the sole fed between the wheels, the sole adjacent to the edge is supported, and prevented from bending down, and provision is made for guiding the edge of

the sole, and for adjustment of the edge-guide, (to vary the width of the skiving, or the distance of a channel from the edge,) and for the pressure upon the upper surface to correspond with such movements of the edge-guide.

I claim, in combination with the smooth-surfaced upper feed-wheel, the toothed-surfaced lower feed-wheel, and the cutter or cutters, arranged to operate upon either surface of the sole, a stationary rest-plate, for supporting the sole and edge to be skived or channelled, substantially as shown and described.

Also, so constructing this rest-plate that the skiving-cutter or its shank can pass through or by the plate from the arm *d*, so as to bring the cutter to the under surface of the sole, substantially as described.

Also, in combination with the feed-wheels and cutter or cutters, arranged to operate as described, an adjustable edge-guide, substantially as described.

Also, in combination with the feed-wheels, stationary rest, and cutter or cutters, arranged to operate on either side of the sole, an adjustable edge-guide, substantially as described.

Also, in combination with the lower feed-wheel, an upper feed or presser-wheel, made adjustable relatively to the edge-guide and the arm by which it is supported, substantially as described

HENRY S. VROOMAN.
